Primary Examiner — Thomas Johannes*Assistant Examiner* — Keith Frank(74) *Attorney, Agent, or Firm* — Saidman DesignLaw Group, LLC(57) **CLAIM**

The ornamental design for a capsule, as shown and described.

DESCRIPTION

FIG. 1 is a top perspective view of a capsule showing my new design;

FIG. 2 is a bottom perspective view thereof;

FIG. 3 is a front view thereof, the rear, left and right side views being identical;

FIG. 4 is a top view thereof;

FIG. 5 is a bottom view thereof;

FIG. 6 is another top view thereof, showing the word "TEXT" in broken lines.

FIG. 7 is a top view of a second embodiment thereof, the bottom perspective, front, rear, left and right side and bottom views being identical to those of the first embodiment;

FIG. 8 is another top view thereof, showing the word "TEXT" in broken lines.

FIG. 9 is a top view of a third embodiment thereof, the bottom perspective, front, rear, left and right side and bottom views being identical to those of the first embodiment;

FIG. 10 is another top view thereof, showing the word "TEXT" in broken lines.

FIG. 11 is a top view of a fourth embodiment thereof, the bottom perspective, front, rear, left and right side and bottom views being identical to those of the first embodiment;

FIG. 12 is another top view thereof, showing the word "TEXT" in broken lines.

FIG. 13 is a top view of a fifth embodiment thereof, the bottom perspective, front, rear, left and right side and bottom views being identical to those of the first embodiment; and, FIG. 14 is another top view thereof, showing the word "TEXT" in broken lines.

It is understood that the drawings include relatively thin surface shading lines that represent contour, not surface ornamentation. The diagonal parallel lines shading lines represent a transparent surface. The horizontal parallel shading lines represent an opaque surface.

The broken lines illustrate unclaimed environment or features which form no part of the claimed design.
